UNITED STATES PATENT OFFICE.

MAURICE LACHMAN, OF NEW YORK, N. Y., ASSIGNOR TO BETHLEHEM STEEL COMPANY, OF BETHLEHEM, PENNSYLVANIA, A CORPORATION OF PENNSYLVANIA.

METAL WHEEL.

1,426,881.

Specification of Letters Patent. Patented Aug. 22, 1922.

Application filed April 30, 1921. Serial No. 465,669.

To all whom it may concern:

Be it known that I, MAURICE LACHMAN, a citizen of the United States, and a resident of New York, in the county of New York and State of New York, have invented certain new and useful Improvements in Metal Wheels, of which the following is a specification.

My invention relates to the construction 10 of metal wheels and more particularly to those in which the rim and spokes are of metal and the rim is supported upon the ends of the spokes.

The object of my invention is to produce 15 a wheel of great strength, lightness and ease of manufacture by utilizing metal bars of the form known commercially as angle bars, to which end my invention consists in the construction and details of construction 20 hereinafter more particularly described and then specified in the claims.

Fig. 1 is a rear elevation of a wheel embodying my invention.

Fig. 2 is a vertical cross-section through 25 the same on the line 2—2 Fig. 1.

Fig. 3 is a rear elevation of a modified structure embodying the invention and

Fig. 4 is a vertical cross-section on the line 4—4 Fig. 3.

Fig. 5 is a cross-section through the form 30 of angle bar employed.

Fig. 6 is a cross-section through one of the spokes.

1 indicates the spokes and 2 the rim of 35 the wheel. The spokes are assembled and secured together in the hub structure in any desired manner but preferably in the manner to be presently described. Each spoke 1 embraces two angle bars of the form illustrated in Fig. 5, said bars being assembled 40 and secured together with the arms 1', 1' presented to one face of the wheel and appearing as one of the spokes of the finished wheel while the two other arms 1'' lie flat 45 against one another and being properly secured together as by spot welding, constitute together a strengthening rib or flange on the rear of the spoke resisting distortion or bending of the spokes in a plane transverse 50 to the general plane of the wheel.

In constructing the wheel I prefer to take a suitable length of angle bar and bend the same into general U form with the legs of the U brought together in the hub structure as illustrated in Fig. 1 of the drawing, or

spread apart as illustrated in Fig. 3 of the drawing. In the one case, as illustrated in Fig. 1, the bases of the U's are assembled as the circumference or rim of the wheel to receive preferably a suitable outer rim 3. 60 Also, and as clearly shown, the U's are assembled with the legs of contiguous U's placed together so that each spoke comprises legs of two of the U's, the remaining legs of which enter into the construction of the 65 spokes to either side thereof. Suitable means may be employed for tying the rim 3 to the angle bar as for instance spot welding.

In the hub structure the arms 1'' forming 70 together the reinforcing ribs of each spoke are located in slots cut into one edge of an annular hub shell 4 which in cross-sectional form, is also like an angle bar, one arm being horizontal and slit inwardly from its one edge while the other arm stands vertically in the finished wheel and is engaged by one of the hub flanges or plates 5. The opposite hub plate or flange 5 engages the faces 1' of each spoke, the whole being suitably clamped together by means of the bolts 80 6 as indicated, to complete the hub structure, wherein the spokes are suitably anchored against circumferential or lateral displacement. Each spoke member may, if desired, have its arms 1'' or part constituting the reinforcing rib tapered as illustrated in the cross-section between the hub and base of the U to add to the appearance and lightness of the wheel. In the hub the ends of 85 the arms or members of the bars presented as the face of the spokes are tapered as shown so that, when assembled in the hub structure, they will be keyed into one another and form a practically continuous hub plate engaged by the hub flange 5 thereby 90 adding to the strength of the hub structure. 95

In the modification of my invention illustrated in Fig. 3 lengths of angle bars are bent to U form but the legs of the U's radiate and the bases of the U's are assembled 100 in the hub structure. The legs terminate in the rim of the wheel, which rim is preferably a circular angle bar 3 against one arm of which, constituting the vertical arm, the faces of the angle bars constituting the 105 spokes are seated, being secured thereto in any desired way. The horizontal arm of the angle bar rim engages the ends of the spokes. In the hub structure the bases of the U bars of which the spokes are formed are seated 110

upon a suitable hub box, as shown, and are fastened in place thereon by being clamped between hub plates or flanges 5, 5' through which fastening bolts 6 pass.

5. What I claim as my invention is:—

1. In a metal wheel, wheel spokes consisting each of two angle bars, two arms of which constitute together the face of the spoke while the two remaining arms lie 10 against one another face to face in a plane transverse to the plane of the wheel and constitute a compound strengthening rib for the spoke, resisting distortion or bending in a plane transverse to the plane of the wheel.
15. 2. In a metal wheel, a spoke structure consisting of lengths of angle bar bent to general U form, with the arms of the U brought together in the spoke structure while the bases of the U's receive and support the rim, 20 the U's being assembled so that the face of each spoke is composed of two bars and the strengthening rib of each spoke consists of the two other arms of the two bars engaging one another face to face in and fastened together so that the plane of both arms will lie 25 in a plane transverse to the general plane of the wheel.
3. In a metal wheel, the combination with U-shaped lengths of angle bar assembled so 30 that the face of each spoke will consist of two arms of contiguous U's each reinforced by a rib the faces of which arms are presented as sides of the spokes while the remaining two arms are fastened together face 35 to face and extend transversely to the plane of the wheel to constitute a reinforcing rib resisting distortion transversely to the plane

of the wheel, a rim secured to the bases of the U's, a slotted hub shell in the slots of which the reinforcing ribs each consisting of two arms fastened together are received and means for securing the free ends of the U's in the hub structure.

4. In a metal wheel, a spoke structure consisting of lengths of angle bar bent to U form and having the U's assembled with the arms of neighboring U's in contact and radiating to the circumference of the wheel and a rim of angle form in cross-section, one of the arms of the angle engaging the ends of the spokes and the other arm being secured in vertical position against arms of the angle bars forming the spokes and having said arms presented to the faces of the wheel, the remaining arms of said angle bars being secured together face to face with the plane of each arm transverse to the plane of the wheel to constitute a rib resisting bending of the spoke transversely.

5. A metal wheel the spokes of which consist of angle bars bent to U form and assembled in contact, each spoke presenting a face formed of one arm of each of two U bars while the remaining arms together form a reinforcing rib for a spoke, the arms forming the face of the spoke being tapered at the ends of the legs of the U to key into one another in the hub structure and form a practically continuous hub plate.

Signed at New York in the county of New 70 York and State of New York this 28th day of April, A. D. 1921.

MAURICE LACHMAN.
